Primary Examiner — Katherine A Holbrow(74) *Attorney, Agent, or Firm* — Studebaker & Brackett
PC(57) **CLAIM**

The ornamental design for a display screen with graphical user interface, as shown and described.

DESCRIPTION

FIG. 1 is a front view of a display screen with graphical user interface showing a second embodiment of our new design; and,

FIG. 2 is an enlarged view of display area thereof.
The outermost broken line rectangle showing a display screen and all other broken lines illustrating portions of the graphical user interface are included for the purpose of illustrating portions of the article and form no part of the claimed design.
